US00D852430S

(12) **United States Design Patent** (10) **Patent No.:** **US D852,430 S**
(45) **Date of Patent:** **** Jun. 25, 2019**

(54) **ANIMAL FEEDER**

(71) Applicant: **9142-9019 QUEBEC INC.,**
Drummondville (CA)

(72) Inventor: **Fernand Roger**, Drummondville (CA)

(73) Assignee: **9142-9019 QUEBEC INC.,**
Drummondville (CA)

(**) Term: **15 Years**

(21) Appl. No.: **29/635,626**

(22) Filed: **Feb. 1, 2018**

(51) LOC (11) Cl. **30-03**

(52) U.S. Cl.

CLAIM

The ornamental design for an animal feeder, as shown.

DESCRIPTION

FIG. 1 is a top perspective view of the animal feeder;
FIG. 2 is a left side view of the animal feeder, the right side
being a mirror image thereof;
FIG. 3 is a front view of the animal feeder;
FIG. 4 is a back view of the animal feeder;
FIG. 5 is a top plan view of the animal feeder; and,
FIG. 6 is a bottom view of the animal feeder.

1 Claim, 6 Drawing Sheets
